SOOT BLOWER

William Davis Ridley, Monkseaton, England

Application December 19, 1942, Serial No. 469,581

7 Claims. (Cl. 122—391)

This invention relates to soot blowers for marine or other high pressure boilers, and particularly to forced draught boilers having a rear combustion chamber and a series of uptake heater tubes arranged at the front of the boiler above the smoke box. The blowers ordinarily employed in these types of boilers are permanent installations, quite complicated in construction and operation, expensive to manufacture and repair, and frequently require considerable auxiliary equipment.

The present invention is intended to dispense with such permanent installations and contemplates a simple and relatively inexpensive portable blower comprising merely a length of pipe and a nozzle therefor, which blower will not only function in the combustion chamber to clean the boiler tubes but will also function in the smoke box to clean the heater tubes and the front tube plate. The nozzle is formed with two series of discharge orifices or ports and is capable of adjustment to select either series for use to the exclusion of the other, the orifices or ports of one series being adapted to direct steam jets against the rear tube plate when the nozzle is positioned in the combustion chamber, and those of the other series being adapted to direct steam jets against the front tube plate as well as the heater tube plate when the nozzle is positioned in the smoke box. Moreover, the discharge orifices of both series, except those used in cleaning the heater tubes, are disposed symmetrically around the nozzle so that a partial turn of the blower in opposite directions will be sufficient to project the steam jets over all of the boiler tubes within different circumferential areas of the tube plates.

When it is desired to clean a boiler, the blower, with the nozzle properly adjusted, is inserted through a simple fixture on the smoke box door and pushed rearwardly through a centrally located boiler tube so as to position the nozzle in the combustion chamber. After the admission of steam, the blower is rocked or turned to and fro and reciprocated back and forth until all of the boiler tubes have been subjected to the action of the steam jets. When the tubes are clean, the blower is withdrawn from the boiler and, after the nozzle has been readjusted, positioned in the smoke box with the heater tube orifices directed upwardly. Steam is again admitted to the blower and the latter is then manipulated in the same manner as before in order that the steam jets from the nozzle will be directed into all of the overlying heater tubes as well as against the entire surface of the front tube plate.

The fixture for the smoke box door provides an entrance to the boiler for the blower and comprises merely a short horizontally disposed tube extending transversely through the door and having an inner bore large enough to accommodate the nozzle. The tube serves as a convenient means of support for the blower when the nozzle is positioned in the smoke box. A screw cap is provided for the tube to close off the entrance when the blower is not in use.

In the accompanying drawings, the invention has been shown merely in preferred form and by way of example, and obviously many changes will readily suggest themselves to those skilled in the art and still be comprised within its spirit. It should be understood, therefore, that the invention is not limited to any specific form or embodiment except insofar as such limitations are specified in the claims.

Referring to the drawings:

Fig. 1 is a vertical section through a boiler, showing the improved blower positioned therein and indicating in broken lines different operative positions of the steam nozzle;

Fig. 2 is a side elevation of the nozzle (actual size), partly in section and broken away to show details of construction;

Fig. 3 is a side elevation of the inner shell of the nozzle, also broken away to show details of construction;

Fig. 4 is a longitudinal section taken on the line 4—4 of Fig. 2;

Fig. 5 is a cross section taken on the line 5—5 of Fig. 2;

Fig. 6 is a cross section similar to Fig. 5 but showing the nozzle in a different adjusted position;

Fig. 7 is a cross section taken on the line 7—7 of Fig. 2 showing the nozzle in the same adjusted position;

Fig. 8 is a side elevation, partly broken away, of a modified form of nozzle; and

Fig. 9 is a side elevation of the smoke box door fixture.

In Fig. 1 the improved blower A is shown properly positioned within a conventional type of marine boiler B having a combustion chamber B¹ at the rear, a smoke box B² at the front, an intermediate bank of fore-and-aft fire tubes B³, and a bank of vertically disposed heater tubes B⁴ located over the smoke box.

The blower A includes a cylindrically shaped nozzle or head A¹ and a suitable length of pipe A² screwed into one end of the nozzle and which 55 is adapted to be connected with a flexible steam

supply hose C in order to permit the manipulation of the blower in the manner already stated. Entrance to the boiler for the blower A is afforded by a tubular fixture B⁵ mounted transversely in the smoke box door and coaxially aligned with a centrally located boiler tube, so that the blower may be passed freely and uninterrupted back and forth therethrough to and from its active position within the combustion chamber B¹. As best shown in Fig. 9, the door of the smoke box is pierced to accommodate the fixture B⁵ and the latter is fastened thereto by means of an integral angularly disposed flange B⁶ adapted to fit against the inclined front face of the door. When the blower is not in use, the entrance is closed off by means of a cap B⁷ (indicated in broken lines) which is screwed on the front end of the tubular fixture.

The nozzle A¹ (see Figs. 2 to 7 inclusive) includes mainly an inner hollow shell A³ and an outer snugly fitting gas-tight sleeve A⁴, which latter is held firmly against the end wall A⁵ of the shell by a clamping nut A⁶ mounted on a stud A⁷ riveted to the end wall A⁵ and projecting axially therefrom through a solid tapered end portion A⁸ of the sleeve. At its opposite end, the sleeve A⁴ is formed with a pair of spaced apart recesses or notches a¹ and a² and abuts, within a few thousandths of an inch, against a correspondingly tapered head portion A⁹ formed on the shell A³ by turning down the body portion thereof to fit the bore of the sleeve. The notches a¹, a² are adapted individually to engage a radially disposed locating pin or projection a³ rising from the shell alongside the head portion thereof, whereby rotary displacement of the sleeve is prevented when it is clamped against the end wall A⁵.

The shell A³ (Figs. 3 and 4) is formed with two series of orifices or ports d¹, d² and communicates directly with the steam pipe A² which is screwed into the head portion A⁹ thereof. The ports d¹ (six in number) are divided into spaced apart groups of three, disposed symmetrically around the body of the shell and drilled therethrough at an angle inclined upwardly and forwardly from the longitudinal axis of the shell; whereas the ports d² (three in number and spaced sixty degrees apart) are drilled through the end wall A⁵ of the shell at an angle inclined upwardly and rearwardly from its longitudinal axis. The sleeve A⁴ is likewise formed with two series of orifices or ports e¹, e² corresponding in number and arrangement with the ports in the shell, the orifices e¹ being drilled through the body of the sleeve at an angle coinciding with that of the ports d¹, and the orifices e² being drilled through the tapered end portion A⁸ thereof at an angle coinciding with that of the ports d². The orifices e¹ and ports d¹ of the corresponding groups are staggered in relation to one another so that steam from the nozzle will cover a greater circular area within a given radius than if those in the different groups were aligned.

The shell A³, for reasons presently to appear, is also formed with an extra pair of horizontally aligned orifices or ports f¹, f² drilled transversely therethrough at right angles to its longitudinal axis, and the sleeve A⁴ is formed with a single orifice or port f³ corresponding with the port f² and aligned horizontally with one of the orifices e¹ in the left-hand group of three shown in Fig. 2.

As the nozzle is thus constructed, by backing

off the clamping nut A⁶, the sleeve A⁴ may be adjusted relatively to the shell A³ to engage either of the notches a¹ or a² with the locating pin a³ and then be locked against displacement in its adjusted position by tightening up the nut A⁶. When the sleeve occupies its adjusted position shown in Figs. 2 and 5, with the notch a¹ engaged with the pin a³, the series of orifices e¹ therein are adapted to register with the ports d¹ in the shell, while the other series of orifices e² are shut off by the end wall A⁵ of the shell. On the other hand, when the sleeve is turned to its other adjusted position, with the notch a² engaged with the locating pin a³, the series of orifices e² therein will register with those in the end wall A⁵, while all but one of the orifices e¹ will be closed off by the body of the shell (see Fig. 6). Under this latter adjustment, the excepted orifice e¹ is adapted to register with the extra port f¹ of the pair in the shell before referred to, and the extra orifice f³ in the sleeve is adapted to register with the other extra port f², so that steam from the nozzle will not only be projected from the orifices e² in the tapered end portion of the sleeve but also through the orifice f³ and the excepted orifice e¹ in the body of the sleeve.

The use of the blower in cleaning a boiler will now be clear: The nozzle A¹ is first adjusted to bring the series of orifices e¹ into use and then, after removing the screw cap B⁷ on the smoke box door, the blower is inserted into the boiler and pushed rearwardly through the central tube, in the manner before described, to its operative position in the combustion chamber B¹. When steam is admitted to the blower, the jets from the nozzle will be directed against the rear tube plate of the boiler and over an exceptionally large area thereof due to the particular angular arrangement and disposal of the orifices around the nozzle. Consequently, when the blower is rocked, say, thirty degrees in opposite directions, and moved intermittently back and forth to carry the nozzle toward and from the tube plate, all of the boiler tubes will be subjected to the action of the steam jets and the cleaning operation may be completed in a relatively short period of time. The blower is now withdrawn from the boiler, the nozzle readjusted to change the direction of the steam jets, and then inserted through the fixture B⁵ to its other operative position within the smoke box B². At this time, jets of steam from the ports f¹, f² will be directed upwardly against the heater tubes B⁴ and those from the ports d² will be directed rearwardly against the front tube plate. Once again, the blower is rocked to and fro and reciprocated back and forth, so that steam from the ports f¹, f² will reach all of the heater tubes and simultaneously steam from the ports d² will reach all of the boiler tubes. When this second cleaning operation is completed, the blower is withdrawn from the boiler and the entrance thereto through the fixture B⁵ is closed off by replacing the cap B⁷.

A modified form of nozzle is shown in Fig. 8. Here it will be noted that the sleeve A⁴ is held resiliently in its adjusted positions by means of a spring G acting through an axially disposed stud G¹ to prevent endwise displacement of the sleeve relatively to the shell A³. The stud G¹ at one end is formed with a rounded head portion G² engaging the tapered end A⁸ of the sleeve, and at its opposite end it is provided with a nut G³ located within the shell. The spring G is arranged between the nut and the opposing end

wall A⁵ of the shell so that its compression will tend to hold the sleeve and shell together and permit the adjustments of the nozzle to be effected in substantially one operation instead of the three required when using the clamping nut A⁶. In other words, with the modified form of nozzle, a change of adjustment may be made by simply pulling out the sleeve A⁴ far enough to turn it from one notch to the other and then, after making the turn, releasing the sleeve and allowing the spring G to engage the newly selected notch with the locating pin a³.

While the blower has been herein described as employing steam for the cleaning operations, it will be understood that compressed air or any other gas under pressure, if available and preferred, could be used to equally good advantage.

Having thus described my invention, what I claim is:

1. A discharge nozzle for a soot blower including, in combination, an inner cylindrical shell closed at one end and open at the other end for connection with the blower pipe and formed at its open end with an annular flange, two series of ports, one series formed in the side wall of the shell and the other in the end wall thereof, an outer cylindrical sleeve snugly fitted to the shell, said sleeve being open at one end to slip over the closed end of the shell and bank against the annular flange thereon and having a head portion for face contact with the closed end of the shell, two series of jet directing orifices, one series formed in the side wall of the sleeve and the other series in the head portion thereof, a pair of recesses formed in the end of the sleeve at its open end, a stud radiating from the shell and arranged to be engaged in one or the other of said recesses, said sleeve being capable of a combined axial and rotary movement on the shell to effect the engagement of the stud in either selected one of the recesses, the relative location of the stud and recesses being such that in one adjusted position of the sleeve the orifices in the side wall thereof will be brought into registry with the ports in the side wall of the shell and the orifices in the head portion of the sleeve located out of registry with the ports in the end wall of the shell, while in the other adjusted position of the sleeve the orifices in the head portion thereof will be brought into registry with the ports in the end wall of the shell and the orifices in the side wall of the sleeve located out of registry with the ports in the side wall of the shell, and means for clamping the sleeve to the shell in either adjusted position of the sleeve.

2. A soot blower including, in combination, a blower pipe of suitable length, a discharge nozzle comprising an inner cylindrical shell fixed to the blower pipe and an outer cylindrical sleeve snugly fitted to the inner shell and capable of both axial and rotary movement thereon, said nozzle shell being formed with two series of ports and said nozzle sleeve with two corresponding series of jet directing orifices, the relative location of the ports and orifices being such that by the rotation of the nozzle sleeve on the nozzle shell either series of jet directing orifices may be brought into registry with the corresponding series of ports while the other series of jet directing orifices are located out of registry with the corresponding series of ports, and means for locking the nozzle sleeve against rotation on the nozzle shell in either of its said adjusted positions, said locking means being rendered effective and ineffective by engagement with and disengagement from the

nozzle sleeve brought about by the axial movement of the nozzle sleeve on the nozzle shell.

3. A soot blower including, in combination, a blower pipe of suitable length, a discharge nozzle comprising an inner cylindrical shell fixed to the blower pipe and an outer cylindrical sleeve snugly fitted to the inner shell and capable of both axial and rotary movement thereon, said nozzle shell being formed with two series of ports and said 10 nozzle sleeve with two corresponding series of jet directing orifices, the relative location of the ports and orifices being such that by the rotation of the nozzle sleeve to one or the other of two different angular positions on the nozzle shell either series of jet directing orifices may be brought into registry with the corresponding series of ports while the other series of jet directing orifices are located out of registry with the corresponding series of ports, a fixed stud or 15 projection radiating from the nozzle shell, a pair of open recesses formed in the nozzle sleeve, one recess being arranged to locate the nozzle sleeve in one of its angular positions on the nozzle shell and the other recess being arranged to locate the 20 sleeve in the other of its angular positions on the nozzle shell, said stud being engageable in one or the other of said recesses by the axial movement of the nozzle sleeve according to the adjusted position of the sleeve, and clamping means 25 30 acting on the nozzle sleeve for maintaining such engagement of the stud and selected recess.

4. A soot blower according to claim 2, wherein one series of ports in the nozzle shell and the corresponding series of jet directing orifices in 35 the nozzle sleeve are each divided into two groups spaced apart in an axial direction and staggered as between groups.

5. A soot blower according to claim 2, wherein both series of ports in the nozzle shell and the corresponding series of jet directing orifices in 40 the nozzle sleeve are disposed symmetrically around the nozzle, whereby the partial rotation of the soot blower when in use will cause the jet directing orifices to cover a complete circum-

- 45 lar zone.
6. In or for a boiler having a combustion chamber, a smoke box and a series of uptake heater tubes, a soot blower positionable in the combustion chamber or the smoke box and adapted to be moved back and forth and rocked to and fro in either position, said soot blower including, in combination, a blower pipe of suitable length, and a discharge nozzle comprising an inner cylindrical shell fixed to said blower pipe 50 and an outer cylindrical sleeve snugly fitted to the inner shell and adjustable thereon to two different angular positions, said shell being formed with three sets of ports and said nozzle sleeve with three corresponding sets of jet directing orifices, 55 one set of ports and the corresponding set of orifices being disposed symmetrically around the nozzle and inclined rearwardly with respect to the axis thereof so as to direct the jets against the rear tube plate of the boiler when the nozzle 60 is located in the combustion chamber, the second set of ports and the corresponding set of orifices also being disposed symmetrically around the nozzle but inclined forwardly with respect to the axis thereof so as to direct the jets against the front tube plate of the boiler when the nozzle 65 is located in the smoke box, and the third set of ports and the corresponding set of orifices being located in endwise alignment at one side of the nozzle and disposed to direct the jets upwardly 70 into the heater tubes when the nozzle is located

in the smoke box, said nozzle sleeve, in one of its adjusted positions, having the first set of its jet directing orifices in registry with the corresponding set of ports in the shell and the other two sets of its orifices out of registry with their corresponding sets of ports in the shell when the nozzle is located in the combustion chamber, and said nozzle sleeve, in the other of its adjusted positions, having the second two sets of its jet directing orifices in registry with their corresponding sets of ports in the shell and the first set of its orifices out of registry with the corresponding set of ports in the shell when the nozzle is located in the smoke box.

7. A discharge nozzle for a soot blower including, in combination, an inner cylindrical shell formed with two series of ports, an outer cylindrical sleeve snugly fitted to the inner shell and

formed with two corresponding series of jet directing orifices, said sleeve being capable of rotary adjustment on the shell to bring either series of orifices in the sleeve into registry with the corresponding series of ports in the shell, and means for locking the sleeve against rotation in either adjusted position, characterized in that the shell is formed with a pair of extra ports spaced apart in an axial direction but disposed in longitudinal alignment, and characterized in that the sleeve is formed with one extra jet directing orifice which is brought into registry with one of said extra ports in one of the two adjusted positions of the sleeve, said sleeve in that particular adjusted position presenting one orifice of the otherwise inactive series in registry with the second extra port in the shell.

WILLIAM DAVIS RIDLEY.
